PETROLEUM NAPHTHALENE MANUFACTURE
Oscar C. Eubank, Long Beach, Calif., assignor to Union
Oil Company of California, Los Angeles, Calif., a cor-
poration of California

Filed Aug. 11, 1961, Ser. No. 130,827
12 Claims. (Cl. 260—672)

This invention relates to the manufacture of naphthalene from source materials of petroleum origin, and in particular concerns an improved process for the production of naphthalene by the catalytic or thermal dealylation of alkyl-substituted naphthalenes obtained from various petroleum refining operations.

The expanding use of naphthalene for the production of dicarboxylic acids useful in manufacturing synthetic resins and fibers has created considerable interest in the manufacture of naphthalene from petroleum hydrocarbons. It is well known that certain hydrocarbon fractions obtained in various petroleum refining operations, e.g., cracking and reforming, contain considerable quantities of alkylnaphthalenes which can be thermally or catalytically dealylated to form free naphthalene. As such processes are conventionally carried out, a feedstock consisting of a reformate or cycle oil fraction boiling above about 430° F. and comprising alkylnaphthalenes and such non-naphthalenic materials as alkylbenzenes, alkyltetralins, alkylindanes, etc., is subjected to dealylating conditions to obtain an effluent product which, after separation of normally gaseous materials such as hydrogen and low molecular weight hydrocarbons, is fractionally distilled to obtain: (1) a light gasoline fraction, (2) a naphthalene fraction, and (3) a heavy fraction comprising unreacted alkylnaphthalenes which, after the removal of heavy ends and polymers, is recycled to the reaction zone. According to one mode of operation, the naphthalene fraction is taken over a relatively wide boiling range, e.g., from about 400° F. to about 435° F., and the naphthalene is recovered therefrom in pure form by low temperature crystallization. However, the relatively low naphthalene content of such a wide boiling range fraction necessitates the processing of a relatively large volume of material and consequently requires the provision of very extensive chilling and crystallization facilities and the cost of refrigerating a large volume of material other than the desired naphthalene. According to a second mode of operation, the naphthalene fraction is taken over a very narrow boiling range, e.g., 420°—427° F., and as such is of sufficient purity to meet many requirements, e.g., conversion into phthalic anhydride. However, when following such mode of operation an appreciable amount of the naphthalene is lost to the gasoline fraction. This occurs by reason of the fact that part of the naphthalene present in the reactor effluent distills over at temperatures below about 420° F. in the form of low boiling azeotropes with other components of the effluent. A portion of the naphthalene is also lost to the heavy fraction boiling above about 430° F., but since such fraction is recycled to the reaction zone, the naphthalene contained therein is eventually recovered in substantially pure form.

The present invention is directed to an improved method for carrying out the second of the above-described procedures, and has for its principal object the recovery of the naphthalene which is ordinarily lost to the gasoline fraction in the form of low-boiling azeotropes. A more general object is to provide an improved method for producing naphthalene by the dealylation of alkyl-naphthalene-containing hydrocarbon mixtures of petroleum origin, and in particular to provide a means for recovering substantially all of the naphthalene present in the dealylation reactor effluent. Other objects of the

2

invention will be apparent to those skilled in the art as the description thereof proceeds.

In accordance with the foregoing objects, the process of the present invention consists in the catalytic or thermal dealylation of a suitable alkylnaphthalene-containing feedstock, after which the dealylation reactor effluent is first treated to remove normally gaseous constituents, and the remaining liquid portion is fractionated to obtain: (1) a gasoline fraction containing light non-naphthalenic materials plus the naphthalene which is associated therewith in the form of low-boiling azeotropes, (2) a naphthalene fraction containing at least about 95 weight percent of naphthalene, and (3) a heavy fraction comprising a small amount of naphthalene, unconverted alkylnaphthalenes, and other materials boiling above naphthalene. The first of said fractions is passed in whole or in part to a low temperature crystallization zone wherein the naphthalene contained in said first fraction is recovered in highly purified form. The second of said fractions is taken as a naphthalene product suitable for direct use in the manufacture of phthalic acid. The third of said fractions is treated to remove heavy ends, and the remainder is returned to the reactor for dealylation of the unconverted alkylnaphthalenes. Such process is based on my discovery that the non-naphthalenic materials which form low-boiling azeotropes with naphthalene do not co-crystallize or form eutectic solids therewith, so that substantially all of the naphthalene which has heretofore been lost to the light gasoline product in the form of azeotropes can be recovered in a highly pure form, e.g., having a melting point of 79.5° C. or better, by subjecting a fraction containing said azeotropes to low temperature crystallization.

In the drawings which form a part of this application, FIGURE 1 thereof takes the form of a flow sheet illustrating one way in which the principle of the invention has been applied to a typical catalytic hydrodealkylation process, and FIGURE 2 illustrates in flow sheet form an alternative mode of operation as applied to a thermal dealylation process. In the interests of simplification, such conventional process equipment as pumps, heat exchangers, reboilers, condensers, reflux lines, phase separators, valves, instrumentation, etc., have been omitted from the drawings.

Referring now to FIGURE 1, the major items of processing equipment include reactor feed column 12, catalytic reactor 14, high pressure gas separator 16, low pressure gas separator 18, gasoline column 20, naphthalene column 22, and a crystallizer-centrifuge combination 24. Light gasoline column 25 is provided to accommodate an optional type of operation, the nature of which is more fully described hereinafter.

The fresh feed, which is suitably an essentially naphthalene-free heavy reformate fraction boiling between about 435° F. and about 735° F. and containing alkyl-naphthalenes and non-naphthalenic materials of the same boiling range, is introduced into the system via feed line 26 and is therein joined by a recycle stream flowing in recycle line 28 and containing unconverted alkylnaphthalenes from a previous cycle of operation. The mixture of fresh feed and recycled material passes from line 26 into feed column 12 which suitably takes the form of a 20-tray bubble cap column operated to produce an overhead fraction boiling between about 435° F. and about 520° F. and a higher boiling bottoms fraction which is withdrawn via line 30 and passed to storage for use as fuel oil or the like.

The overhead fraction from feed column 12 is passed via line 32 into reactor feed manifold 34 wherein it is joined by a mixture of water vapor and a hydrogen-containing recycle gas stream flowing in line 38. Make-up hydrogen and water are introduced into line 38 from

lines 40 and 42, respectively. The reactor feed mixture, comprising the hydrocarbons taken overhead from column 12, hydrogen and water, is passed to reactor feed heater 44 wherein it is heated to an incipient reaction temperature, and the heated mixture is passed via line 46 to catalytic reactor 14 at such rate that the space velocity with the reactor is about 0.4 volume of hydrocarbon per hour per volume of catalyst. About 8100 s.c.f. of hydrogen and about 0.085 barrel of water are provided per barrel of hydrocarbon in the reactor feed mixture.

Reactor 14 contains a fixed bed of a dealkylation catalyst consisting of a silica-stabilized alumina base having supported thereon about 3.0 weight percent of cobalt oxide, about 9.0 weight percent of molybdenum oxide, and about 2.2 weight percent of sodium oxide. The reaction zone is maintained at a temperature of about 1100° F. and a pressure of about 1000 p.s.i.g., and a substantially uniform temperature profile within the catalyst bed is maintained by introducing a quench gas consisting of a part of the hydrogen-containing recycle gas flowing in line 38 into the reaction zone at a plurality of points along the length thereof via lines 47. About 1430 s.c.f. of the quench gas are employed per barrel of hydrocarbon in the reactor feed.

The reactor effluent passes from reactor 14 through effluent cooler 48 wherein it is cooled to about 160° F., and thence into high pressure separator 16 which is operated at a pressure only slightly below that of reactor 14. Within separator 16 the cooled effluent separates into a gaseous phase, a liquid hydrocarbon phase and an aqueous phase. The latter is withdrawn via line 50 and is either discarded or recycled back to the reactor feed manifold. The gaseous phase, which comprises hydrogen and a relatively small amount of normally gaseous hydrocarbons, is withdrawn from separator 16 and passed to line 38 for use as the reactor quench gas and for recycle to the reactor feed manifold. The liquid hydrocarbon phase in separator 16 is withdrawn via line 52 and is passed through pressure relief valve 54 into low pressure separator 18 which is operated at or near atmospheric pressure. Within separator 18 the dissolved normally gaseous hydrocarbons flash off to form a gaseous phase which is withdrawn and passed via line 56 to storage for use as fuel gas or the like. The liquid hydrocarbon phase which forms in separator 18 is passed to light gasoline column 20 via line 58.

Column 20 is operated to produce in line 60 an overhead fraction comprising light non-naphthalenic materials and essentially all of the naphthalene which is associated therewith in the form of low-boiling azeotropes. The cut point will vary somewhat depending on a number of factors, but will typically be about 420° F. The bottoms fraction from column 20 is passed via transfer line 62 to naphthalene column 22 which is operated to produce in line 64 an overhead fraction constituting a naphthalene product of about 98.5 percent purity having a melting point of about 78.5 C. Typically, column 22 is operated at a cut point of about 425° F., so that the naphthalene product in line 64 has a boiling range of about 420°-425° F. The bottoms fraction from column 22, containing a certain amount of naphthalene, unconverted alkynaphthalenes, non-naphthalenic hydrocarbons of similar boiling range and high boiling polymers and the like is passed via line 66 to recycle line 28 for return to reactor feed column 12.

The gasoline fraction produced in line 60 is passed through three-way control valves 68 and 70 to crystallizer-centrifuge 24. The crystallizer section of the latter takes the form of a conventional scraped surface chiller wherein the feed stream is cooled to a temperature of about -10° F. over a period of about 45 minutes to effect crystallization of the naphthalene. From the crystallizer section the slurry of naphthalene crystals in mother liquid is passed directly to the centrifuge section wherein the crystals are separated from the mother liquor. Suitably,

the crystals are washed in the centrifuge with a light hydrocarbon such as pentane, and are then stripped to remove traces of the wash liquid by means not shown. The naphthalene product analyzing 99+% pure and having a melting point of about 80° C. is passed to storage via line 72, and the mother liquor from the centrifuge is withdrawn through line 74 and is passed to storage for use as a gasoline blending stock or otherwise.

In the event it should be desired to decrease the size of crystallizer-centrifuge 24, light gasoline column 25 is provided to separate the gasoline column overhead into a substantially naphthalene-free overhead fraction and a bottoms fraction comprising the low-boiling naphthalene azeotropes. When following such mode of operation, valve 68 is rotated clockwise to send the gasoline overhead to light gasline column 25, and valve 70 is rotated counter-clockwise to send the bottoms from column 25 to crystallizer-centrifuge 24. Column 25 is suitably operated at a cut point of about 400° F., so as to produce in line 76 a substantially naphthalene-free 400° F. end-point gasoline, and to pass to the crystallizer-centrifuge only that portion of the column 20 overhead which boils over the range 400° F.-420° F.

Considering now the process of the invention in somewhat greater detail, it is adapted to the dealkylation of any petroleum hydrocarbon mixture containing alkyl-naphthalenes and materials which, in the dealkylated product, cause the formation of low-boiling azeotropes with naphthalene. Catalytically or thermally cracked cycle oils and heavy reformate fractions are most commonly employed, with platinum-catalyzed reformate fractions being particularly preferred. A particularly preferred process feedstock of this type consists of a platinum-catalyzed reformate fraction boiling between about 435° F. and about 675° F. and comprising 40-70 percent alkynaphthalenes. A second preferred feedstock consists of a thermally or catalytically cracked cycle oil extract fraction obtained, for example, by subjecting a TCC or FCC cycle oil of suitable boiling range to hydro-refining (i.e., hydrodesulfurization and/or hydrodenitrogenation) in the presence of a cobalt molybdate catalyst (Unifining), and subjecting the hydrorefined product to solvent extraction (e.g., with sulfur dioxide or a glycol) to obtain an extract product rich in naphthalene and naphthalene precursors. Alternatively, the cycle oil can first be solvent extracted and the aromatics-rich extract then hydrorefined to obtain a suitable feedstock. With particularly "clean" cycle oils (i.e., low sulfur and/or low nitrogen) the hydrorefining step can be omitted. Also, when the dealkylation reaction is effected thermally, the pre-removal of sulfur and/or nitrogen from the feedstock need not be complete and in some instances (depending on the sulfur and nitrogen specifications for the naphthalene product) may be omitted entirely.

Since the process of the invention is directed to the recovery in substantially pure form of the naphthalene which heretofore has been lost in the form of low-boiling azeotropes, and since the non-naphthalenic hydrocarbons which form such azeotropes with naphthalene occur in the reactor effluent regardless of whether the dealkylation reaction is effected catalytically or thermally, the advantages of the process are attained with both types of operation. When carried out catalytically, the reaction is usually effected in the presence of hydrogen, and the catalyst usually comprises an oxide or sulfide of one or more of the metals of groups VIB and VIII of the periodic system supported on an adsorbent carrier. Suitable active components include the oxides and/or sulfides of tungsten, molybdenum, chromium, iron, cobalt, nickel, and mixtures thereof. These active components are supported in minor amounts (e.g., 1-20 weight percent) upon carriers such as alumina, silica, titania, zirconia, zinc oxide, activated clays, and the like, or mixtures thereof. Supports which normally have relatively high cracking activity are preferably deactivated

by including minor amounts of alkalinizing components, e.g., sodium oxide, in the catalyst composition. The catalyst may be maintained in the form of a fixed bed, a compact moving bed, or a fluidized bed. Typical catalytic dealylation conditions include a reaction temperature between about 900° F. and about 1250° F., preferably between about 950° F. and about 1150° F., a reaction pressure between about 700 and about 1600 p.s.i.g., and a liquid hourly space velocity of between about 0.2 and about 5 volumes of hydrocarbon per hour per volume of catalyst. When the reaction is carried out in the presence of hydrogen, as is usually the case, between about 3000 and about 15,000 s.c.f. of hydrogen (usually in the form of a recycle gas containing 70-95 volume percent of hydrogen) are provided per barrel of hydrocarbon. The use of water vapor to moderate the reaction in accordance with the teachings of Doumani, U.S. Patent No. 2,734,929, is a valuable expedient, with the water vapor being provided in an amount representing between about 0.04 and about 0.15 barrel of liquid water per barrel of hydrocarbon. When employing a fixed bed catalyst, it is also desirable to maintain the temperature gradient within the bed at a value below about 100° F. by introducing a hydrogen-containing quench gas into the reaction zone at a plurality of points along the length thereof as described previously in connection with FIGURE 1.

Typical thermal dealylation conditions include a reaction temperature between about 1000° F. and about 1500° F., preferably between about 1100° F. and about 1250° F., a reaction pressure between about 200 and about 1000 p.s.i.g., and a reaction time of between about 2 and about 20 seconds. Conventionally, thermal dealylation is likewise carried out in the presence of hydrogen, with between about 2000 and about 10,000 s.c.f. of hydrogen being provided per barrel of hydrocarbon. It is also conventional to effect thermal dealylation within a fixed, compact moving, or fluidized bed of a non-catalytic inert material, such as sand, pebbles, Alundum chips, and the like.

In general, then, the dealylation reaction may be carried out under any of the wide variety of conditions known to effect the dealylation of alkyl-substituted hydrocarbons such as alkylnaphthalenes.

The effluent which is withdrawn from the reaction zone is initially treated to separate gaseous from liquid constituents, e.g., by condensation. When hydrogen is employed in the reaction zone it is preferably recovered as a separate gaseous stream for recycle purposes by initially condensing the reactor effluent at an elevated pressure, after which the normally gaseous hydrocarbons (which for the most part have remained dissolved in the liquid hydrocarbon components) are flashed off by reducing the pressure to a substantially lower value, e.g., atmospheric pressure. The remaining liquid components of the reactor effluent are then passed to the fractionation and crystallization operations which constitute the heart of the invention.

As previously stated, the fractionation operation is carried out to effect the isolation of the following fractions enumerated in order of increasing boiling range: (1) a gasoline fraction containing non-naphthalenic components and substantially all of the naphthalene which distills in the form of low-boiling azeotropes, (2) a naphthalene product fraction which contains at least about 95 weight percent of naphthalene, (3) a heavy fraction which contains unconverted alkylnaphthalenes and non-naphthalenic hydrocarbons of similar boiling range, and which is recycled to the dealylation zone, and (4) a high-boiling fraction which comprises polymeric materials and the like and which is taken as a process product useful as fuel oil or the like.

It will be apparent that while certain of the cut points between these respective fractions are more critical than others, a certain degree of latitude is permitted depend-

ing on the desired purity of the naphthalene fraction and the extent to which it is desired to recover the naphthalene which occurs in the form of low-boiling azeotropes. Also, the cut points will vary somewhat with the various process parameters. Thus, in FIGURE 1 the cut point at which gasoline column 20 is operated to produce the first of the fractions identified above will depend upon the boiling points of the naphthalene-containing azeotropes present, which boiling points in turn depend upon the nature of the feedstock and the reaction conditions. It will also depend on the desired purity of the second of said fractions. Where maximum quantity, rather than maximum purity, of the second fraction (naphthalene column overhead) is the primary consideration, the cut point of the gasoline column may be set relatively low, e.g., at about 415° F. On the other hand, a more highly purified second fraction may be obtained (at the expense of losing some of the non-azeotroped naphthalene to the first fraction) by setting the cut point somewhat higher, e.g., at about 420° F. or even slightly higher. Thus, in FIGURE 1, column 20 is usually operated to produce an overhead fraction having a maximum true boiling point between about 415° F. and about 420° F.

The cut point between the second and third of the above-identified fractions is likewise governed by the desired naphthalene content of the second fraction. By setting the cut point at a relatively low value, e.g., at about 425° F., a high concentration of naphthalene is obtained in the second fraction at the expense of losing some naphthalene to the third fraction (which naphthalene, however, is eventually recovered), whereas by setting such cut point at a relatively high value, e.g., at about 435° F., a somewhat less concentrated naphthalene product fraction is obtained. Thus, in FIGURE 1, column 22 is operated to produce an overhead fraction having a maximum true boiling point between about 425° F. and about 435° F., preferably between about 425° F. and about 430° F.

The cut point between the third and fourth of the above-identified fractions is least critical of all, and is governed primarily by the nature of the dealylation step and the feedstock employed. Desirably, such cut point is selected to separate materials capable of further dealylation from materials which undergo no useful reaction in the dealylation zone. Usually, the latter materials boil above about 485° F., so that, in FIGURE 1, column 12 is operated to produce an overhead fraction having a maximum true boiling point of at least about 485° F. but not greater than about 550° F., preferably about 510° F.

As has been previously described, the first of the fractions identified above may be further fractionated to produce a low-boiling overhead fraction which is substantially naphthalene-free (e.g., containing less than about 1 weight percent of naphthalene) and a bottoms fraction which contains naphthalene associated with non-naphthalenic materials in the form of low-boiling azeotropes. When following such mode of procedure optimum operation is usually attained when this fraction is carried out to produce an overhead fraction having a maximum true boiling point between about 395° F. and about 405° F., usually about 400° F.

Selection of the two alternative ways for handling the first of the above-identified essential fractions (i.e., passing the entire fraction to the crystallization operation versus further fractionation to separate a substantially naphthalene-free fraction and passing the remainder to the crystallization operation) is primarily a matter of economics. Since the first mode of operation requires handling a larger volume of material in the crystallization operation, more extensive crystallization facilities and higher refrigeration costs are involved. On the other hand, while the second mode of operation per-

mits a reduction in these items, an additional distillation column is required.

The crystallization step is carried out in the conventional manner, i.e., by cooling the feed stream to a relatively low temperature to obtain a slurry of naphthalene crystals in mother liquor, and thereafter separating the crystals by filtering or centrifuging. Preferably, the cooling is effected in a scraped surface chiller taking the form of a jacketed conduit through which the feed stream is passed. Scrapers adapted to be rotated against the walls of the conduit are provided to prevent crystalline material from building up on the walls of the conduit and interfering with the transfer of heat therethrough. Conventionally, the jacket is divided into two or more sections through which different refrigerants are circulated at successively lower temperatures. The temperature to which the crystallizer feed stream is cooled and the rate at which such cooling is effected depend on the desired purity of the product and the means and conditions employed for separating the crystals from the mother liquor. In the practice of the present invention I have found it satisfactory to chill the feed to a temperature between about -20° F. and about 0° F., preferably between about -15° F. and about -5° F., over a period of 30-60 minutes when employing a centrifuge for separating the crystals from the mother liquor. Usually it is desirable to wash the crystals with a light hydrocarbon wash liquid, e.g., pentane, light gasoline, etc., and to remove traces of the wash liquid by steam stripping, distillation, etc. If necessary, the naphthalene product may be treated with clay or acidic salts in the known manner to remove color bodies. The mother liquor recovered from the crystallization operation is suitable for use as a gasoline blending stock. In general, then, in effecting the crystallization step any of the techniques and equipment customarily employed in such type of operation may be employed, and any of the known treatments for the purification of petroleum or coal tar naphthalene may be applied in the practice of the present process.

Referring now to FIGURE 2, the process thereby illustrated employs thermal dealkylation and an alternative fractionation scheme. The feedstock, which consists of a platinum-catalyzed reformate fraction boiling over the range 475°-570° F. and containing about 43.7 weight percent of mono-methylnaphthalenes, about 33.0 weight percent of higher alkyl naphthalenes, with the remainder being non-naphthalenic hydrocarbons, is introduced into the process system via line 100 and is therein joined by the liquid portion of the reactor effluent flowing in line 102. The mixture is introduced into feed column 104 which is operated to produce in line 106 an overhead fraction having a maximum boiling point of about 510° F. Said fraction is introduced from line 106 into reactor feed manifold 108 and the bottoms fraction is passed to storage via line 112.

The reactor feed mixture flowing in manifold 108 is admixed with about 5000 s.c.f./bbl. of hydrogen introduced into the system from line 110, and passes through feed preheater 114 which is operated to preheat the reactor feed to about 900° F. The heated feed then passes through line 116 to reactor 118 within which the dealkylation is effected. Reactor 118 consists of a fire-brick lined shell filled with 2-inch Alundum balls, and is maintained at a temperature of about 1325° F. and a pressure of about 650 p.s.i.g. The reactor feed is passed therethrough at such a rate as to maintain a contact time therein of about 10 seconds.

The hot reactor effluent is withdrawn from the reactor through line 120 to effluent cooler 122 wherein it is cooled to ambient temperature, and the cooled and condensed effluent is passed to gas-liquid separator 124 to effect separation of normally gaseous components. The latter are withdrawn through line 126 as a product make gas which may be employed as such for fuel or treated by conventional methods to separate a hydrogen-rich stream

suitable for recycling to reactor feed manifold 108. The liquid portion of the reactor effluent is withdrawn from separator 124 and is passed via transfer line 128 to gasoline column 130.

Gasoline column 130 is operated to produce in line 132 an overhead fraction having a maximum boiling point of about 420° F. Said fraction is introduced from line 132 into light gasoline column 134 which is operated to produce in line 136 an overhead fraction of substantially naphthalene-free light gasoline having a maximum boiling point of about 400° F. The bottoms fraction from column 130 is passed via line 138 to naphthalene column 140 which is operated to produce in product line 142 an overhead fraction boiling between about 420° F. and about 427° F. and containing about 98.6 weight percent naphthalene. The bottoms fraction from column 140, comprising unconverted alkyl naphthalenes and other components of the reactor effluent boiling above about 427° F., is passed to recycle line 102 for return to feed column 104 and further dealkylation.

The bottoms fraction from column 134, comprising azeotroped naphthalene and non-naphthalenic materials boiling between about 400° F. and about 420° F., is passed via line 144 to chiller 146. The latter is of the conventional scraped surface type, the jacket of which is divided into three sections 146a-146c to provide for the use of three different refrigerants at successively lower temperatures. Cold (50° F.) water is circulated through section 146a, chilled (-8° F.) methanol through section 146b, and cold (-40° F.) methanol through section 146c. The residence time of the feed within the chiller is about 45 minutes, and the temperature of the slurry which is withdrawn from the downstream end through line 148 is about -10° F. From line 148, the slurry passes to centrifuge 150 wherein the crystals are separated from the mother liquor. Within the centrifuge the crystals are washed with a stream of cold pentane introduced from line 152, and the washed crystals are withdrawn through line 154 and passed to heater 156. Within the latter the naphthalene crystals are melted, and the molten naphthalene is passed to a small stripping column 158 which is operated to produce in line 160 the pentane adhering to the crystals taken from the centrifuge. The bottoms product from stripper 158, constituting substantially pure (99.9%) naphthalene, is passed to storage through product line 162. The mother liquor is withdrawn from the centrifuge via line 164, and is passed to stripper 166 which is operated to produce the pentane wash liquid in overhead line 168 and pentane-free mother liquor in line 170. The recovered pentane flowing in lines 160 and 168 is returned to line 152 for re-introduction into centrifuge 150. Make-up pentane may be added as needed from line 172.

Other modes of applying the principle of my invention may be employed instead of those explained, change being made as regards the methods or materials employed provided the step or steps stated by any of the following claims, or the equivalent of such stated step or steps, be employed.

I, therefore, particularly point out and distinctly claim as my invention:

1. In a process wherein an alkyl naphthalene-containing petroleum hydrocarbon feedstock boiling above about 430° F. and selected from the class consisting of catalytic reformates, catalytically cracked cycle oils and thermally cracked cycle oils is passed, together with added hydrogen, through a dealkylation zone maintained at an elevated temperature and an elevated pressure sufficient to effect dealkylation of a substantial amount of said alkyl naphthalene, whereby there is obtained a dealkylation zone effluent comprising naphthalene and non-naphthalenic hydrocarbons which form low-boiling azeotropes with naphthalene, the improvement which comprises fractionating said effluent to obtain a first fraction containing at least about 95 weight percent of naphthalene, a second fraction

having a boiling range below that of said first fraction and comprising azeotroped naphthalene, and a third fraction having a boiling range above that of said first fraction and comprising alkynaphthalenes; returning an alkynaphthalene-containing portion of said third fraction to said dealkylation zone; cooling a naphthalene-containing portion of said second fraction in a crystallization zone to effect the formation of crystalline naphthalene; and separating said crystalline naphthalene from the mother liquor.

2. A process as defined by claim 1 wherein substantially all of said second fraction is cooled in said crystallization zone.

3. A process as defined by claim 1 wherein said second fraction is further fractionated to obtain a low-boiling substantially naphthalene-free portion and a higher boiling portion comprising azeotroped naphthalene; and said higher boiling portion is cooled in said crystallization zone.

4. A process as defined by claim 1 wherein said dealkylation zone contains a catalyst comprising a mixture of the oxides of molybdenum and cobalt supported on an alumina base, and is maintained at a temperature between about 900° F. and about 1250° F. and a pressure between about 700 p.s.i.g. and about 1600 p.s.i.g., and hydrogen is introduced into said dealkylation zone in an amount representing between about 3000 s.c.f. and about 15,000 s.c.f. per barrel of hydrocarbon introduced into said zone.

5. A process as defined by claim 1 wherein said dealkylation zone contains a non-catalytic solid material, and is maintained at a temperature between about 1000° F. and about 1500° F. and at a pressure between about 200 p.s.i.g. and about 1100 p.s.i.g., and hydrogen is introduced into said dealkylation zone in an amount representing between about 2000 s.c.f. and about 10,000 s.c.f. per barrel of hydrocarbon introduced into said zone.

6. The process for obtaining naphthalene which comprises (1) forming a feed mixture comprising the herein-after identified recycle stream, fresh petroleum hydrocarbon feedstock boiling above about 430° F. and containing a substantial amount of alkynaphthalenes, and hydrogen, said feedstock being selected from the class consisting of catalytic reformate, catalytically cracked cycle oils, and thermally cracked cycle oils; (2) passing said feed mixture into a dealkylation zone maintained under conditions of elevated temperature and elevated pressure sufficient to effect the dealkylation of a substantial amount of said alkynaphthalenes; (3) withdrawing a dealkylated effluent from said dealkylation zone and condensing said effluent to obtain a liquid effluent phase and a gaseous effluent phase; (4) distilling said liquid effluent phase to obtain a first fraction boiling between about 420° F. and about 430° F. and containing at least about 95 weight percent of naphthalene, a second fraction having a boiling range below that of said first fraction, and a third fraction having a boiling range above that of said first fraction; (5) returning an alkynaphthalene-containing portion of said third fraction to the aforesaid step (1) as said recycle stream; (6) introducing a naphthalene-containing portion of said second fraction into a crystallization zone maintained at a low temperature sufficient to effect crystallization of a substantial amount of the naphthalene introduced therein; and (7) separating the crystalline naphthalene so formed from the mother liquor.

7. A process as defined by claim 6 wherein, in step (6), substantially all of said second fraction is introduced into said crystallization zone as said naphthalene-containing portion of said second fraction.

8. A process as defined by claim 6 wherein said second fraction is further fractionated to obtain a low-boiling substantially naphthalene-free portion and a higher boiling portion containing azeotroped naphthalene; and said higher boiling portion is introduced into said crystalliza-

tion zone as said naphthalene-containing portion of said second fraction.

9. A process as defined by claim 6 wherein said dealkylation zone contains a catalyst comprising a mixture of the oxides of molybdenum and cobalt supported on an alumina base, and is maintained at a temperature between about 900° F. and about 1250° F., and at a pressure between about 700 p.s.i.g. and about 1600 p.s.i.g., and hydrogen is introduced into said dealkylation zone in an amount representing between about 3000 s.c.f. and about 15,000 s.c.f. per barrel of hydrocarbon introduced into said zone.

10. A process as defined by claim 6 wherein said dealkylation zone contains a non-catalytic solid material, and is maintained at a temperature between about 1000° F. and about 1500° F. and at a pressure between about 200 p.s.i.g. and about 1100 p.s.i.g., and hydrogen is introduced into said dealkylation zone in an amount representing between about 2000 s.c.f. and about 10,000 s.c.f. per barrel of hydrocarbon introduced into said zone.

11. The process for obtaining naphthalene which comprises (1) forming a feed mixture comprising the herein-after identified recycle stream, a platinum-catalyzed petroleum hydrocarbon reformate fraction boiling above about 430° F. and containing a substantial amount of alkynaphthalenes, and between about 3000 and about 15,000 s.c.f. of hydrogen per barrel of hydrocarbon; (2) contacting said feed mixture with a fixed bed of a dealkylation catalyst comprising a mixture of the oxides of molybdenum and cobalt supported on silica-stabilized alumina containing a minor amount of an alkali, said contacting being effected at a liquid hourly space velocity of between about 0.2 and about 5 volumes of hydrocarbon per hour per volume of catalyst and at a temperature between about 900° F. and about 1250° F. and a pressure between about 700 and about 1600 p.s.i.g.; (3) withdrawing a dealkylated effluent from said dealkylation zone and fractionating it to obtain: (a) a normally gaseous fraction, (b) a substantially naphthalene-free light gasoline fraction having a maximum boiling point of about 405° F., (c) a higher boiling naphthalene-containing first intermediate fraction having a maximum boiling point of about 420° F., (d) a naphthalene fraction containing at least about 95 weight percent naphthalene, (e) a higher boiling second intermediate fraction having a maximum boiling point of about 550° F., and (f) a higher boiling bottoms fraction; (4) returning said second intermediate fraction to the aforesaid step (1) as said recycle stream; (5) cooling said first intermediate fraction to a temperature between -20° F. and about 0° F. to effect crystallization of the naphthalene contained therein; and (6) separating the crystalline naphthalene so formed from the mother liquor.

12. A process as defined by claim 11 wherein said catalyst comprises a silica-stabilized alumina base having dispersed thereon about 3 weight percent of cobalt oxide, about 9 weight percent of molybdenum oxide, and about 2.2 weight percent of sodium oxide, said feed mixture contains water vapor in an amount corresponding to between about 0.04 and about 0.15 barrel of liquid water per barrel of hydrocarbon, and hydrogen is introduced into said catalyst bed at a plurality of points along the length thereof and in an amount sufficient to maintain the temperature gradient therein at a value below about 100° F.

UNITED STATES PATENT OFFICE
CERTIFICATE OF CORRECTION

Patent No. 3,193,593

July 6, 1965

Oscar C. Eubank

It is hereby certified that error appears in the above numbered patent requiring correction and that the said Letters Patent should read as corrected below.

Column 10, line 15, for "tmeperature" read -- temperature --; line 50, for "between -20° F." read -- between about -20° F. --.

Signed and sealed this 28th day of December 1965.
